UNITED STATES PATENT OFFICE.

ARTHUR A. MERRITT, OF WORCESTER, MASSACHUSETTS, ASSIGNOR TO WILLCOX & GIBBS SEWING MACHINE CO., OF NEW YORK, N. Y., A CORPORATION OF NEW YORK.

ADJUSTABLE SHAFT-COUPING.

1,363,140.

Specification of Letters Patent. Patented Dec. 21, 1920.

Application filed July 30, 1919. Serial No. 314,213.

To all whom it may concern:

Be it known that I, ARTHUR A. MERRITT, a citizen of the United States of America, and a resident of Worcester, Massachusetts, have 5 invented a new and useful Improvement in Adjustable Shaft - Couplings, which invention is fully set forth in the following specification.

The present invention is an improvement 10 upon shaft couplings such as shown in Figure 9 of patent to me No. 1,041,652, dated October 15, 1912. While designed particularly for use in sewing machines, the improved coupling may be used wherever two 15 shafts are to be joined together end to end, to operate as one, and it is desirable and necessary in such joinder to accurately correlate the shafts with respect to the positions to which they are respectively turned 20 about their axes; in other words, to accurately determine and adjust the axial positions of the shafts with relation to each other. For example, in my patent aforesaid, Fig. 9 (which is a rear elevation of 25 the machine) shows the main driving shaft in two sections. The shaft section 81 has driving connections for actuating the loopers and other parts which operate below the work-plate, while the shaft section 80 30 has driving connections which actuate the needles and other parts operating from above the work-plate. These two sets of mechanism must be accurately set with relation to each other, and this is determined 35 by the relative axial positions of their respective shaft sections. If the loopers are late in passing the needles to engage loops of needle threads, or if the condition is the reverse, it then becomes desirable to readjust 40 the relative axial positions of the shaft sections to advance, or set back, the operation of the loopers: in other words, to correlate or time the operation of the two sets of mechanism.

45 The main object of the present invention is to provide, as part of the coupling, means for making accurate axial adjustment of the two shafts, or shaft sections, joined by the coupling. This and other objects, such as 50 the provision of a simple, durable and inexpensive adjustable coupling, are attained by what I now regard as the preferred embodiment.

ment of the invention illustrated in the accompanying drawings, wherein—

Fig. 1 is a plan view;

55

Fig. 2 is a longitudinal section; and

Figs. 3 and 4 illustrate the action of the device in axially adjusting one shaft section relative to another.

Referring to the drawings, 10 and 11 are 60 shafts, or shaft sections, respectively. 12 is a coupling member or sleeve having tapered exteriorly screw-threaded ends, each engaged by a nut 13. The ends of sleeve 12 are split longitudinally so as to be capable 65 of expansion or contraction as the nuts are tightened or loosened thereon. A set-screw 14, working in a threaded opening through the wall of sleeve 12, has a rounded inner end adapted to engage a seat or depression 70 in shaft section 10. An adjusting member or plug 16, screw-threaded in an opening through the wall of sleeve 12, is rotatable on an axis at right angles to and intersecting the axis of the sleeve member. Two projecting pins 17, 17, on plug 16 are adapted to be engaged by any suitable implement for turning the plug; and a scale along the periphery of the upper face of the plug, in juxtaposition to a zero-mark on the sleeve, 75 accurately indicates the position to which the plug is turned. A set-screw 18 works in a threaded opening through the plug 16 eccentrically positioned with relation to the axis of the latter. The inner rounded end 80 of set-screw 18 engages a groove 19 extending longitudinally of the shaft section 11 and preferably of concave cross-section.

In the position of the parts shown in Figs. 1 and 2, the two shaft sections are rigidly 90 joined by the coupling with the groove 19 of one shaft section in longitudinal alignment with the seat 14 of the other shaft section (as shown in Fig. 3), the nuts 13, 13 being tightened to forcibly contract the 95 split ends of the sleeve into secure engagement with their respective shaft sections, and the set-screws 14 and 18 being screwed in to tightly engage seat 15 and groove 19 respectively. If it be desired to change the 100 relative axial positioning of the shaft sections, say by rotating shaft section 11 in the direction of the arrow, Fig. 4, nut 13 is loosened to release the contraction of the

sleeve against shaft section 11, the set-screw 18 is loosened, but not sufficiently to disengage it from groove 19, and the adjusting member or plug is rotated toward the letter F (Fig. 1) which is inscribed on the sleeve 12. By such rotation of 16, the inner end of the eccentrically positioned set-screw 18 may be caused to travel from its medial position shown in Fig. 3 to its position indicated in Fig. 4, and, in so doing, it moves along and coöperates with groove 19 to rotate shaft section 11 in the direction of the arrow, Fig. 4. Rotation of adjusting member 16 in the opposite direction will rotate the shaft section 11 in the reverse direction. After the desired adjustment has been thus attained, sleeve 12 is again contracted, to securely grip the shaft section 11, by tightening nut 13, and the set-screw 18 is set into tight engagement with groove 19.

What is claimed is:—

1. A shaft coupling including in combination a coupling sleeve for embracing the ends of two shafts or shaft sections to be coupled together, an adjusting member carried by said coupling sleeve and operable to adjustably rotate one shaft relatively to the other to which it is coupled, and a nut engaging a tapered screw-threaded and longitudinally split end of the sleeve for contracting the same against the adjusted shaft to secure the same when the desired adjustment has been attained.

2. In a shaft coupling, the combination of a coupling member and an adjusting member rotatably mounted on said coupling member to turn upon an axis approximately radial to the axis of said coupling member and operable by its rotation to adjustably rotate one shaft relatively to the other to which it is coupled.

3. In a shaft coupling, the combination of a coupling sleeve for embracing the ends of two shafts or shaft sections to be coupled thereby, and an adjusting member rotatably mounted in the wall of said sleeve and operable by its rotation to adjustably rotate one shaft relatively to the other to which it is coupled.

50 4. In a shaft coupling, the combination of a coupling member and an adjusting member rotatably mounted on said coupling member to turn upon an axis approximately transverse to the axis of said coupling member, said adjusting member having thereon an eccentrically positioned projection engaging one shaft to adjustably rotate it relatively to the other shaft to which it is coupled.

60 5. In a shaft coupling, the combination of a coupling sleeve for embracing the ends of two shafts or shaft sections to be coupled thereby, and an adjusting member rotatably mounted in an opening in the wall of said sleeve to turn on an axis approximately

radial to the axis of said sleeve and operable by its rotation to adjustably rotate one shaft relatively to the other to which it is coupled.

6. In a shaft coupling, the combination 70 of a coupling sleeve, and an adjusting member mounted on said sleeve to rotate on an axis approximately transverse to the axis of the sleeve, said adjusting member having thereon an eccentrically positioned projection 75 engaging one shaft to adjustably rotate it relatively to the other shaft to which it is coupled.

7. In a shaft coupling, the combination 80 of a coupling sleeve, and an adjusting member mounted on said sleeve to rotate on an axis approximately radial to the axis of the sleeve said adjusting member having thereon an eccentrically positioned projection 85 engaging a groove in one shaft to adjustably rotate the same relatively to the other shaft to which it is coupled.

8. In a shaft coupling, the combination 90 of a coupling sleeve for embracing the ends of two shafts or shaft sections to be coupled together, an adjusting member rotatable in an opening in the wall of the coupling sleeve and on an axis approximately radial to the axis of said sleeve, and a connection 95 between said adjusting member and one shaft to adjustably rotate the latter relatively to the other shaft by the rotation of said adjusting member.

9. In a shaft coupling, the combination 100 of a coupling sleeve to embrace the ends of two shafts, clamping means for contracting each end of the sleeve against its shaft for securing the shafts in the sleeve against rotation, and means on the sleeve operable to rotatably adjust one of said shafts relatively to the other shaft when said first named shaft is released by its clamping means.

10. In a shaft coupling, the combination 110 of a coupling sleeve for embracing the ends of two shafts or shaft sections to be coupled together, a plug screw-threaded in an opening through the wall of the sleeve, and a set-screw in an opening through the plug eccentric to its axis and engaging one shaft 115 to adjustably rotate it relatively to the other shaft upon rotation of the plug.

11. In a shaft coupling, the combination 120 of a coupling sleeve for embracing the ends of two shafts or shaft sections to be coupled together, a plug screw-threaded in an opening through the wall of the sleeve, and a projection on said plug eccentric to its axis and engaging one shaft to adjustably rotate it relatively to the other shaft upon rotation 125 of the plug.

In testimony whereof I have signed this specification.

ARTHUR A. MERRITT.
